UNITED STATES PATENT OFFICE.

WILLIAM H. PRATT, OF CUMMINSVILLE, NEBRASKA.

SCREW DRIVER.

Application filed May 26, 1926. Serial No. 111,833.

This invention relates to certain new and useful improvements in screw drivers, and has more particular reference to a device of this kind particularly adapted for holding and starting the driving of screws into work within restricted and confined places.

An object of the invention is to provide means applicable to the shank of a screw driver for effectively holding a screw in operative engagement with the driving bit of the screw driver, with the screw properly held in position for being started into the work.

A further object is to provide a screw holding means of the above kind which is extremely simple and durable in construction as well as efficient in operation, and which may be readily engaged and disengaged from the screw.

A still further object of the invention is to provide means whereby the screw holding device is caused to rotate with the screw driver so as to aid the bit of the screw driver in turning the screw.

Other objects will appear as the nature of the invention is better understood, and the same consists in the novel form combination and arrangement of parts hereinafter more fully described, shown in the accompanying drawing and claimed.

In the drawing, wherein like reference characters indicate corresponding parts throughout the several views,

Figure 1 is a front elevational view of a screw driver equipped with a screw holding means constructed in accordance with the present invention, and illustrating a screw held in effective driving engagement with the bit of the screw driver;

Figure 2 is a side elevational view of the device shown in Figure 1;

Figure 3 is a view similar to Figure 1 with the screw holding device in substantially central longitudinal section; and

Figure 4 is a fragmentary section taken substantially upon line 4-4 of Figure 1.

Referring more in detail to the drawing, the screw driver proper consists of a suitable elongated shank 5 having a suitable form of handle 6 fixed upon one end thereof and having its other end flattened and suitably shaped to provide an integral driving bit 7 adapted to engage in the usual transverse groove or kerf of the head of the screw 8 which is desired to be driven into work within confined or restricted places.

In accordance with the present invention the screw driver proper is provided with a screw holding means including a frame, generally indicated at 9, of open elongated form. This frame is mounted at its inner end upon the shank 5 for sliding movement longitudinally of the latter, and the other end of the frame is provided with a transverse slot opening through one edge of the frame as at 10 so that the shank of the screw may be engaged in said slot 10 with the head of the screw bearing upon the inner side of the adjacent end of the frame 9, whereby the screw is disposed in alignment with the shank 5 for being properly driven into the work. In order to effectively hold the screw in place with the bit 7 maintained effectively in engagement in the kerf of the screw head, the frame 9 is suitably yieldingly urged in an inward direction on the shank 5 or toward the handle 6.

As shown, the frame 9 consists of a single strip of metal bent into narrow elongated U-shape so as to present a pair of relatively long legs or free end portions 11 parallel with and at opposite sides of the screw driver shank 5, and a relatively short intermediate or transverse connecting portion 12 disposed adjacent to but outwardly of the bit 7 and formed with the slot 10. The frame further embodies a collar 13 to opposite sides of which are attached the free end portions of the legs 11, and which is slidably mounted for movement longitudinally on the shank 5 of the screw driver proper, the attachment of the legs 11 to the collar 13 being effected by suitable means such as screws 14 passing through the legs 11 and threaded into the collar 13 as shown clearly in Figure 3.

The means for yieldingly urging the frame 9 toward the handle 6 preferably consists of a helical compression spring 15 disposed on the shank 5 and between the collar 13 and the bit 7 with its ends respectively engaging said collar 13 and bit 7. With the frame 9 thus yieldingly urged inwardly the head of the screw will be effectively brought into driving engagement with the bit 7 so that the screw is effectively held in place in alignment with the shank 5 for being properly driven into the work when the screw driver proper is rotated, or turned. Naturally, after the screw 8 has been sufficiently started into the work, the present invention may be disengaged from the said screw by simply pulling outwardly upon the handle 6 so as to compress the spring 15

and disengage the bit 7 from the head of the screw, after which the present invention is moved laterally bodily so as to permit the frame to move out of engagement with the screw by the latter riding out of the transverse slot 10.

The frame 9 is preferably turned with the shank 5 when the device is in use so as to avoid any friction by reason of turning of the head 19 of the screw relative to the portion 12 of the frame engaged thereby. This is also desired because the frame will then aid the bit 7 in turning the screw. For this purpose the inner end of the bit 7 is preferably provided 15 with lateral lugs or wings 16 which project outwardly from the side edges of the bit and slidably engage in longitudinally elongated slots 17 provided in the legs 11 of the U-shaped frame member. Obviously, this construction insures driving of the frame so that 20 it is turned with the shank 5 when the screw is being driven into the work, and at the same time the screw driver proper is permitted to shift longitudinally relative to the frame 25 when disengaging the bit from the head of the screw.

From the foregoing description it is believed that the construction and operation as well as the advantages of the present invention will be readily understood and appreciated by those skilled in the art.

Minor changes may be made without departing from the spirit and scope of the invention as claimed.

35 What I claim as new is:—

1. In a screw holding screw driver, a relatively long shank having one end formed to provide a bit designed to engage at the free forward edge in the kerf of a screw, an elongated substantially U-shaped frame having 40

45 said shank arranged longitudinally and between the legs thereof, said bit being located adjacent the yoke portion of the frame, laterally projecting spurs formed integral with said bit for engagement in adjacent longitudinally extending slots in the frame legs, said yoke portion of the frame having a recess formed in one side edge to receive the shank of a screw for engagement by the bit, means loosely mounted upon said shank for connecting the free ends of the frame legs together, and resilient means normally urging said bit toward the yoke portion of the frame.

2. A screw holding screw driver of the character described, comprising an elongated shank having one end formed to provide a relatively broad bit having the side edges straight and substantially parallel, an elongated U-shaped frame having shank extending longitudinally and between the legs 55 thereof with said bit located therein adjacent the yoke portion, the side edges of said bit moving between and contacting with the opposed inner faces of the frame legs, laterally projecting spurs formed integral with said 60 bit and designed to extend through adjacent apertures formed longitudinally of the frame legs, said frame having one side edge of the yoke portion provided with a recess to receive the shank of a screw in position for engagement by said bit, a sleeve carried by said shank and arranged between the free ends of said legs and having the legs secured thereto, and a spring member surrounding the shank 65 between said sleeve and said bit and normally urging the bit toward the frame yoke.

In testimony whereof I affix my signature.

WILLIAM H. PRATT.
